UNITED STATES PATENT OFFICE.

WILLIAM L. WATERALL, DECEASED, LATE OF PHILADELPHIA, PENNSYLVANIA, BY
JOHN CLIFFORD JONES, ADMINISTRATOR, OF PHILADELPHIA, PENNSYLVANIA.

TAG-SECURING MEANS.

1,160,347.

Specification of Letters Patent. Patented Nov. 16, 1915.

Application filed July 2, 1914. Serial No. 848,665.

To all whom it may concern:

Be it known that WILLIAM L. WATERALL, deceased, late a citizen of the United States of America, residing in the city and county 5 of Philadelphia, in the State of Pennsylvania, did invent certain new and useful Improvements in Tag-Securing Means, of which the following is a true and exact description, reference being had to the accompanying drawings, which form a part thereof.

The present invention consists in an improved form of label or tag, and means for securing the label or tag against a curved 15 surface, such as the cylindrical or conical outer surface of a metallic pail or can receptacle in which paint and like commodities are stored, sold and transported.

The object of the invention is to provide a 20 tag or label which can be readily attached to a receptacle after the latter has been filled, which will be durable and not easily defaced, and will remain fresh and attractive in appearance after a considerable interval 25 of time; and which is adapted to be applied to the side, rather than to the top, of a pail or can receptacle.

In the paint trade, for which the invention is of especial value, paints and pigments 30 are frequently stored for comparatively long intervals before leaving the plant of the makers. In such case, it is desirable not to attach the label or tag to the receptacle before the time for shipping the receptacle, in order to entirely avoid any discoloration or fading or other deterioration 35 in appearance of the tag, which might occur during the period in which the filled receptacle is stored, if previously applied. The receptacles are frequently shipped loose, so that 40 if a paper label, for instance, be pasted on the side of the receptacle, it is apt to be defaced, or rubbed off the receptacle in transit.

The location of the label or tag on the side 45 of the receptacle, rather than on its top, is desirable for a number of reasons. When the receptacles are stacked up one on top of another, as is frequently the case, each upper receptacle then covers the tag or label of the 50 subjacent receptacle. Furthermore, the label is apt to be scratched by the receptacle above it and to be defaced by dirt collecting thereon, and occasionally by leakage from the upper receptacle. Furthermore, when a recep-

tacle of this character is opened, the user 55 ordinarily throws away the cover, thereby destroying all further advertising value of the label or tag.

To secure the advantages and to avoid the disadvantages referred to above, tag or label 60 is made in the form of a sheet metal plate, on which the legend or illustration constituting the label proper may be applied in any suitable manner, advantageously by lithographing; and the paint pail or other 65 receptacle or object to which the tag is to be applied is provided with simple and effective provisions whereby the tag is snugly held against the curved surface of the object.

The various features of novelty characterizing the invention are pointed out with particularity in the claims annexed to and forming a part of this specification. For a better understanding of the invention, however, and of the advantages possessed by it, reference 70 should be had to the accompanying drawings and descriptive matter, in which is illustrated and described a preferred form in which the invention may be embodied.

Of the drawings: Figure 1 is an elevation of a metallic receptacle to which the invention is applied; Fig. 2 is a section on the line 2-2 of Fig. 1; Fig. 3 is a section on the line 3-3 of Fig. 1.

In the drawings, A represents a metallic 85 vessel, such as the iron or steel pail or can in which white lead and other paints and pigments are stored, sold and transported. Attached to the outer curved surface of the receptacle is a pair of oppositely disposed 90 lugs or clips B, which, advantageously, as shown, are arranged at the same distance from the ends of the pail. Advantageously, as shown, each clip is attached to the body of the receptacle by two rivets C, and may 95 be so attached at the time the receptacle is originally made. The tag is in the form of a rounded plate or disk D of sheet metal, the matter forming the label proper being printed, painted, or otherwise suitably applied to the outer surface of the disk. The opposite edges of the disk are received in the grooves or channels provided between the outer surface of the receptacle and the inner edges of the clips B (see Figs. 2 and 100 3). The clips are so shaped and disposed that the channels each of which is open at both ends and along its side facing the

other lug or clip, snugly receive diametrically opposed portions of the disk D, which may be sprung into place and held there by its own resiliency. When so held the plate is 5 also held by its own resiliency in snug contact with the curved outer surface of the receptacle A. Advantageously, the slips and disk may be relatively arranged to make it 10 more difficult for the disk to become displaced after it is once put in place. For instance, the disk may be formed with radial rib portions or outstruck projections D' at its periphery, each adapted to spring into a groove or outstruck seat B' formed in the 15 inner side of the corresponding clip B, when the disk D is put in place.

With the construction described, it will 20 be apparent that a tag may be put in place, and removed and replaced by another if necessary, rapidly, and with comparative ease. The tags have their label markings applied while in the flat, and can be cheaply made. When these tags are in the form 25 of plates of painted or enameled sheet metal, *i. e.*, lithographed tin, they can be made very attractive in appearance, and very durable, thus facilitating an advantageous display of such receptacles after a period sufficiently long to make ordinary 30 paper labels dingy and unattractive in appearance. The cost of lithographing, or otherwise marking and ornamenting a flat tag disk, is of course appreciably less than the cost of similarly marking and ornamenting the outer curved surface of the 35 receptacle itself.

While in accordance with the provisions 40 of the statutes, the preferred form of the invention is illustrated and described, it will be apparent to those skilled in the art that changes may be made in the form of apparatus disclosed without departing from the spirit of the invention, and that under 45 some conditions certain features of the invention may be used without a corresponding use of other features.

Having now described the invention, what is claimed as new and desired to be secured by Letters Patent, is:

50 1. The combination with a metal receptacle having a curved outer surface, of a tag in the form of a metal plate, and means for detachably securing said tag against the curved outer surface of said receptacle

comprising lugs secured to the latter at 55 points angularly displaced with reference to the axis of curvature of said receptacle and shaped to provide channels or grooves each open at both ends and along its side facing the other lug, said channels being 60 adapted to receive and hold oppositely disposed portions of the edge of said tag.

2. The combination with a metal receptacle having a curved outer surface, of a tag in the form of a normally flat resilient 65 rounded metal plate, and means for detachably securing said tag against the curved outer surface of said receptacle comprising lugs secured to the latter at points angularly displaced with reference to the axis 70 of curvature of said receptacle and adapted to receive portions of the edge of said plate which are oppositely disposed and are short in comparison with the maximum dimension of the engaged plate in a direction parallel 75 to said axis, whereby said plate when engaged by said lugs is held by its own resiliency snugly against the curved outer surface of said receptacle.

3. The combination with a metal receptacle having a curved outer surface and provided with a pair of lugs angularly displaced with respect to the axis of curvature of said receptacle, said lugs having their opposed edges separated from said surface 85 to provide tag receiving channels each open at both ends and at its side opposed to the other lug, of a tag in the form of a plate of sheet metal having opposed edge portions received in said channels, said tag 90 being held by its own resilience snugly against said surface.

4. A label holder for articles having a substantially cylindrical body portion, comprising lugs on said body provided with 95 outwardly extending portions and having outstruck seats therein, and a flexible label plate having outstruck projections, said plate being adapted to conform to said body by being sprung into and secured to said 100 portions by said projections fitting in said seats.

JOHN CLIFFORD JONES,
Administrator of the estate of William L.
Waterall, deceased.
